Primary Examiner — Jennifer Rivard*Assistant Examiner* — Jenny lou M Binas(74) *Attorney, Agent, or Firm* — Grossman, Tucker, Perreault & Pfleger, PLLC**CLAIM**

The ornamental design for a wand vacuum, as shown and described.

DESCRIPTION

FIG. 1 is a perspective view of a wand vacuum, showing our new design;

FIG. 2 is a left side view of the wand vacuum of FIG. 1; FIG. 3 is a right side view of the wand vacuum of FIG. 1; and,

FIG. 4 is a top view of the wand vacuum of FIG. 1. The broken lines are included for the purpose of illustrating portions of the wand vacuum that form no part of the claimed design.

1 Claim, 3 Drawing Sheets# US D1,015,660 S
